UNITED STATES PATENT OFFICE.

WILLIAM F. HUNTER, OF OAKLAND, CALIFORNIA, ASSIGNOR OF THREE-FOURTHS TO
SAN FRANCISCO BRIDGE CO., OF SAN FRANCISCO, CALIFORNIA.

SPIRAL TUNNEL ENTRANCE.

Application filed June 9, 1923. Serial No. 644,472.

To all whom it may concern:

Be it known that I, WILLIAM F. HUNTER, a citizen of the United States, residing at Oakland, in the county of Alameda and 5 State of California, have invented a new and useful Spiral Tunnel Entrance, of which the following is a specification.

This invention relates to subway, tunnel and tube structures, and more particularly 10 to a novel form of approach employed at the ends.

The primary object of the invention is to provide an approach that will eliminate the necessity of occupying or acquiring valuable 15 property for straightaway approaches, and thereby reducing the cost of subway and tube construction to a minimum.

Another object of the invention is to decrease the distance to be travelled in passing 20 through the subway, as, on account of the smaller diameter of circle and steeper grade for the descending traffic, as compared with that of the larger diameter of circle and easier grade for ascending traffic, makes 25 a substantial saving in the total distance to be traversed.

A still further object of the invention is to provide approach structures which may be constructed at a location remote from 30 the subway, and readily floated and sunk into position, as this would, in many cases, effect a substantial saving in cost of construction. Where the conditions are advantageous, the excavation may be made 35 and the approach structures constructed directly in position.

This form of approach structure may be used in connection with two tubes, one for traffic in each direction, or it may be used 40 in connection with a single tube carrying traffic in both directions.

With the foregoing and other objects in view which will appear as the description proceeds, the invention resides in the 45 combination and arrangement of parts and in the details of construction hereinafter described and claimed, it being understood that changes in the precise embodiment of the invention herein disclosed, may be made 50 within the scope of what is claimed, without departing from the spirit of the invention.

Referring to the drawings:

Figure 1 is an elevational view disclosing approaches constructed in accordance 55 with the invention, as supplied at the ends of a subway construction.

Figure 2 is a vertical sectional view through an approach constructed in accordance with the invention. 60

Figure 3 is a diagrammatical view of the invention.

Referring to the drawings in detail, the reference character 5 designates the wall of the approach, which may be formed of sheet 65 metal, wood, concrete or other material, the same being circular or polygonal in formation, as clearly shown by Figure 3 of the drawings.

The reference character 6 designates a 70 spirally-arranged roadway supported by the posts 7 and 8, the posts 8 providing a dividing line dividing the roadway of the approach, into lateral traffic ways permitting uninterrupted traffic in opposite directions. 75 A tower is indicated at 9 and is disposed substantially centrally of the approach, the tower being provided with openings 10 at the upper end and pipes 10' at the lower end to ventilate the subway. 80

A winding stairway designed at 11 encircles the tower 9, whereby pedestrians may use the approach to facilitate traffic. An elevator or series of elevators for 85 pedestrians may also be installed in the tower or at other convenient location.

As shown, the subway, which may be of any desired construction, is indicated at 12, and may embody either a pair of tubes or a single tube which connects with a spirally-arranged road surface through the openings 13. 90

In the use of the device, it is to be understood that an approach as shown and described, is to be employed at opposite ends of a subway, thereby reducing the grade ordinary necessary in ascending from a subway to the minimum, and at the same time reducing the ground surface required for the usual long approaches to the minimum. 95

It is contemplated in construction of the approach structures of this character either to construct them in their permanent position after excavating the ground, or to con- 100

struct them at points remote and to convey them to their proper places and sink them, as for example, at the edges of rivers or bodies of water, wherein subways are to be built thereunder.

5 What I claim is:—

An approach for subways including a circular metallic body portion adapted to be sunk in a body of water, the body portion being formed of water-proof material, 10 a spirally arranged road surface within the

body portion, said road surface communicating with a subway, and posts for supporting the road surface.

In testimony that I claim the foregoing as 15 my own, I have hereto affixed my signature in the presence of two witnesses.

WILLIAM F. HUNTER.
